UNITED STATES PATENT OFFICE

148,621

DESIGN FOR A WRENCH

Fred Herman, Cleveland, Ohio

Application July 24, 1946, Serial No. 131,876

Term of patent 14 years

(Cl. D54—16)

To all whom it may concern:

Be it known that I, Fred Herman, a citizen of the United States, residing in the city of Cleveland, county of Cuyahoga, and State of Ohio, have invented a new, original, and ornamental Design for a Wrench, of which the following is a specification, reference being had to the accompanying drawing, forming a part thereof.

Figure 1 is a view of one side of the wrench showing my new design;

Figure 2 is a view of the wrench in open condition;

Figure 3 is a view of the other side of the wrench in its closed condition;

Figure 4 is a rear end view of the wrench;

Figure 5 is a front end of the wrench.

I claim:

The ornamental design for a wrench, substantially as shown.

FRED HERMAN.
